UNITED STATES PATENT OFFICE.

JOHN H. HERBENER, OF NORFOLK, VIRGINIA

FLAG.

1,398,376.

Specification of Letters Patent. Patented Nov. 29, 1921.

Application filed March 25, 1921. Serial No. 455,423.

To all whom it may concern:

Be it known that I, JOHN H. HERBENER, a citizen of the United States, residing at Norfolk, in the county of Norfolk and State 5 of Virginia, have invented certain new and useful Improvements in Flags, of which the following is a specification.

My invention relates to flags and has particular reference to improvements in the flag 10 shown and described in my copending application for flags and method of producing the same, Serial No. 372,930, filed August 10, 1920.

An important object of the invention is to 15 provide additional reinforcements for the free end portion of the flag, which will coact with the retarding stitchings, extending substantially parallel with the free edge of the flag, thus preventing the retarding stitchings from being blown out and breaking.

A further object of the invention is to provide a peculiarly strong reinforcing means for the corners of the flag, near the free edge thereof.

Other objects and advantages of the invention will be apparent during the course 25 of the following description.

In the accompanying drawings forming a part of this specification, and in which like 30 numerals are employed to designate like parts throughout the same,

Figure 1 is a side elevation of a flag embodying my invention, and,

Fig. 2 is an enlarged fragmentary side 35 elevation of the free end portion of the flag.

In the drawings, wherein for the purpose of illustration is shown a preferred embodiment of my invention, the numeral 10 designates a flag as a whole, which for the purpose of illustration, is a United States flag.

The numeral 12 designates the red stripes, and 13 the white stripes, formed of suitable cloth. These stripes are sewed together by felling or otherwise, as shown at 14 in 45 Fig. 2. The numeral 15 designates the blue field of the flag, having stars 16 sewed therein. This field is secured to the stripes, by sewing or felling, as is well known.

The free ends of the stripes 12 and 13 are

left raw, that is, these ends are not hemmed 50 or bound, and the free edge of the flag is accordingly left raw.

The free end portions of the stripes 12 and 13 are provided with a plurality of spaced retarding stitchings 17 and 18 respectively. These retarding stitchings may be spaced for any suitable distance, such as from an eighth of an inch to three fourths of an inch, or more, depending largely upon the size of the flag. The retarding stitches 60 17 and 18 are preferably arranged in alignment, and constitute continuous retarding stitchings extending substantially parallel with the raw edge of the flag. The stitchings 17 are red to correspond with the color 65 of the stripes 12, and the stitchings 18 white to correspond with the color of the stripes 13, these stitchings being preferably sewed upon the stripes before the stripes are assembled and stitched together. I preferably provide a fringe 19, outwardly of the outer retarding stitchings, which is formed by unraveling the warp or transverse threads of the stripes, the fringe being formed by the ends of the longitudinal woof threads. 70 This fringe may vary in length from about an eighth of an inch to a half inch, or more, depending upon the size of the flag. The fringe materially improves the appearance 75 of the flag and also retards to some extent, 80 the wearing of the raw edge.

I have found by actual experimentation and tests, that the retarding stitchings sometimes break, when the flag is wet and is subjected to high wind, and I have provided means which I have found prevents this breakage, to a considerable extent. This means consists of V-shaped stitchings 20 and 20', upon each stripe. The base of the V-shaped stitching 20 is arranged outermost, 85 while the apex of the V-shaped stitching 20' is arranged outermost and the apices of both V-shaped stitchings are disposed in the central longitudinal axis of the stripe. The ends of the V-shaped stitching preferably 90 terminate at or in the longitudinal stitchings of the stripes. I preferably employ 95 the stitchings 20 and 20' combined, while

I may employ either alone, or I may increase the number of each stitching 20 or 20', as desired. The V-shaped stitchings extend across and over all of the retarding stitchings and prevent such retarding stitchings being blown out and thereby broken. The V-shaped stitchings are preferably formed upon the several stripes, before they are assembled and stitched together, and the 10 V-shaped stitchings form in effect a continuous serpentine stitching.

I have found that there is a marked tendency for a flag to wear at the corners, adjacent its free end and this wearing usually 15 commences at the outer apex of the corner, and works inwardly in a diagonal direction. To overcome this, I provide a special stitching reinforcement for the upper and lower corner stripes. This stitching embodies a plurality of elliptical or loop stitching 21, which taper forwardly, and are arranged to form a fan shape group, diverging diagonally and rearwardly. This corner stitching reinforcement may be placed 25 upon the corner stripes before they are assembled with the other stripes.

In producing the several retarding and reinforcing stitchings, I preferably employ a thread which is wiry in strength and 30 silky in smoothness, and I also preferably employ a lock stitch.

By the provision of a flag of the above described character, the hem at the free end of the flag is entirely dispensed with, and 35 the free end left raw. This eliminates the weight at the free end, which acts as a whip-cracker, tending to break the fabric immediately behind the hem. With the arrangement of stitchings or reinforcement, 40 herewith shown and described, I produce a flag which has an increased life, and in addition possesses a more pleasing and graceful appearance when being flown.

When the free end of the flag tends to wear 45 or fray, it is cut off immediately inwardly of the outermost retarding stitching, and a new edge produced. The wind removes the warp threads in advance of the next retarding stitching; again forming a fringe.

50 It is to be understood that the form of my invention herewith shown and described is to be taken as a preferred example of the same, and that various changes in the shape, size, and arrangement of parts may 55 be resorted to without departing from the spirit of my invention, or the scope of the subjoined claims.

Having thus described my invention, I claim:

60 1. A flag of the character described having its free edge raw and provided near such raw edge with spaced retarding stitches arranged substantially parallel

with said raw edge, said flag also having stitchings extending across the retarding 65 stitches and serving to bind them to the flag.

2. A flag of the character described having its free edge raw and provided near such raw edge with spaced retarding 70 stitchings extending generally in the direction of such raw edge, said flag also having stitchings extending transversely of the retarding stitchings and serving to attach the same to the flag. 75

3. A flag of the character described having its free edge raw and provided near such raw edge with retarding stitching means, and separate stitching serving to bind the retarding stitching means to the 80 flag.

4. A flag of the character described having its free edge raw and provided with a plurality of spaced retarding stitches extending longitudinally of such edge, and 85 substantially V-shaped stitchings formed upon the flag and extending over and across the retarding stitchings.

5. A flag of the character described having its free end raw and provided at the 90 free end with a fringe, and retarding stitching means secured to the flag near the free end.

6. A flag of the character described having its free end raw and provided near the free 95 end with retarding stitching means extending longitudinally of the free edge, stitchings extending transversely across the retarding stitching means, and separate reinforcing stitchings at the outer corners of 100 the flag.

7. A flag of the character described having its free edge raw and provided with retarding stitching means extending longitudinally of said edge, said flag having reinforcing stitchings formed upon its outer corners, said reinforcing stitchings increasing in width rearwardly. 105

8. A flag of the character described having its free edge raw and provided with 110 retarding stitching means near the free edge, and reinforcing stitching loops formed upon the outer corners of the flag, said loops being arranged in fan shaped groups increasing in width rearwardly. 115

9. A flag of the character described provided near its outer corners with reinforcing stitching loops, said loops being arranged in substantially fan shaped groups increasing in width rearwardly. 120

10. A flag of the character described provided near its outer edge with spaced stitchings extending longitudinally of such edge, stitchings extending transversely of the retarding stitchings and serving to bind them 125 to the flag, and reinforcing stitching loops

formed upon the outer corners of the flag, said loops being arranged in substantially fan shaped groups.

11. A flag of the character described having its free edge raw and provided near the free edge with a plurality of spaced retarding stitchings extending longitudinally of the free edge, said flag also having substantially V-shaped stitchings extending 10 over the retarding stitchings with their apices arranged outermost.

12. A flag of the character described hav-

ing its free edge raw and provided near the free edge with a plurality of spaced retarding stitchings extending longitudinally of the free edge, said flag further having two sets of substantially V-shaped stitchings extending over the retarding stitchings, the V-shaped stitchings in one set extending in an opposite direction to 20 the V-shaped stitchings in the other set.

In testimony whereof I affix my signature.

JOHN H. HERBENER.
